UNITED STATES PATENT OFFICE.

STEPHEN D. LAYMAN, OF NEWARK, NEW JERSEY.

LAST.

1,146,266.

Specification of Letters Patent. Patented July 13, 1915.

Application filed December 23, 1914. Serial No. 878,645.

To all whom it may concern:

Be it known that I, STEPHEN D. LAYMAN, a citizen of the United States, and a resident of Newark, county of Essex, and State 5 of New Jersey, have invented certain new and useful Improvements in Lasts, of which the following is a specification.

My invention is directed to the improvement of that type of last wherein the body 10 of the last is provided with a movable block held in place by two pins inclined toward one another, one of which is fixed, and the other is spring-pressed outwardly and so arranged that it may be pushed back into 15 the body of the last against its spring.

It is to the improvement of the spring-pressed pins or fasteners used in lasts of this type that my invention is particularly directed. Such fasteners as are now commonly found on the market comprise a sleeve, a spring within the sleeve and a pin also received within the sleeve and reduced in diameter for a portion of its length, in which portion it is encircled by the spring 25 and the whole arrangement driven in place in an opening provided in the body block. Such arrangement has numerous disadvantages in that, for example, a driving fit is relied on to hold the device in place, and 30 it may become loosened upon changes occurring in the wood due to varying conditions of heat and moisture; such devices are likely to be injured while being driven in place; it is necessary to provide a ferrule in the 35 opening in the block to reduce the opening if both the opening in the block and that in the body are formed at one time and of the same diameter, as is most conveniently done; if, for any reason, it is necessary to remove 40 the fastener, it is very difficult to take it out if it happens to be tightly wedged or driven in place; the cost of such fasteners, including sleeves, is a considerable item in the production of a large number of lasts in 45 the factory, and other difficulties arise with such fasteners which need not be further referred to here.

According to the present invention a very much simplified construction is obtained, and the difficulties inherent in such former structures are done away with.

With the foregoing and related objects in view, my invention consists in the parts,

improvements and combinations herein set forth and claimed. 55

A form of last embodying my invention is illustrated in the accompanying drawing forming a part of this specification and wherein the same reference numerals are applied to designate the same parts throughout.

In said drawing, Figure 1 is a perspective view of a last body, the block being detached. Fig. 2 is a fragmentary side view of the last shown in Fig. 1 with the block in 65 place on the body, certain parts being shown in cross-section, and Fig. 3 is a fragmentary cross-sectional view on the line 3—3, Fig. 2.

The body or main portion of the last is designated by the reference numeral 10, and 70 the detachable block which, together with the body, makes up the complete last, by the reference numeral 11. The stationary pin for holding the toe of the block in place on the body is designated by the reference numeral 12, and the recess in the toe of the block 11 in which the pin 12 is received, by the reference numeral 13. The guide recess for guiding the pin 12 into the recess 14 is shown at 14. A bore 15 is formed in 80 the upper portion of the block and preferably at one side thereof, and such bore is continued into the last body, as shown at 15^a. Such bores 15 and 15^a are preferably made at one time by boring through the 85 block in place and into the last body, as in this way accurate registration can most conveniently be obtained. The bore 15, 15^a is placed at an angle to the longitudinal axis 90 of the pin 12, as is customary.

The pin 16 is received within the bore 15^a and has an upper part 17 of the original diameter, a reduced portion 18 adjacent thereto, a part 19 of the original unreduced diameter and terminates in a stud 20 of reduced 95 diameter and preferably of the same diameter as the intermediate reduced portion 18. The pin 16, which is preferably of cylindrical form, is preferably made by turning down a rod, as of steel, of original diameter 100 slightly less than the diameter of the bore 15, 15^a. Such pins can readily be made by automatic machinery in large quantities and at small expense. A coil spring 21 is received at the bottom of the bore 15^a and 105 bears against the shoulder formed between

the portions 19 and 20 of the pin, the reduced portion 20 entering the coil spring 21 and centering the spring 21 with respect to the pin 16. The purpose of the reduced portion 18 is to provide a recess for receiving a stop to control the in and out movement of the pin 16, and in the form of construction shown, such stop has the form of a cross-pin 22 which is received within a bore 23 in the body portion 10 of the last. With this arrangement the cross-pin 22 serves as a stop for the movement of the pin 16 in both directions. Normally it is pushed outward by the spring 21 until the enlarged portion 19 thereof rests against the stop pin 22. When the pin 16 is pushed inward against the spring 21 the stop pin 22 serves as a means for defining the limit of the inward movement of the pin 16 by the enlargement 17 coming in contact therewith. The enlarged portions 17 and 19 are always in contact with the interior of the bore 15^a and, fitting therein fairly close but not sufficiently close to bind, give a double sliding bearing at separated points, thus insuring that there will be no binding of the pin in its movement in and out of the bore 15^a. Furthermore, if, as sometimes happens in the rough treatment to which lasts are submitted in the shoe factory, a blow is struck on the projecting portion 17, as by a hammer, or if the projecting end 17 of the pin 16 is given a severe wrench, as in removing the movable block 11 or putting the same in place upon the last, the double bearing at separated points provided by the enlargements 17 and 19 prevents any harm from being done to pin or last by such treatment, since with such double bearing at separated points the pin is not easily gotten out of shape or broken by being subjected to blows or other rough treatment.

The method of fastening the block in place and of detaching it is that usually practised with lasts of this kind. To fasten the block in place it is inserted in the recess provided for that purpose, the pin 12 entering the guideway 14 and being guided thereby into the opening 13, and the block being pressed against the body to retract the pin 16 into its seat until it comes opposite the opening of the bore 15 in the block, when it springs into the seat provided for it by said bore, thus holding the block against removal; and to remove the block the pin 16 is pushed down by a suitable tool inserted within the mouth of the bore 15, thus permitting the movement of the block 11 across the end of the pin 16 and its consequent ready removal from the last body.

It will be seen that a fastener constructed in accordance with my invention has numerous advantages: It is extremely cheap, there is no occasion for a preliminary assembly of the parts prior to insertion in the opening

provided for their reception, all that is necessary to secure such fastener in place being to insert the spring 21 and pin 16 in the bore 15^a with the stud 20 entering the central opening in the spiral spring, and to drive the cross-pin 22 into the cross-bar provided for that purpose, the pin 16 being meanwhile held down so that the cross-pin 22 may enter the recess surrounding the reduced portion 18 and between the enlarged parts 17 and 19. While the cross-pin 22 is here shown as passing entirely through the last body and at one side of the reduced part 18, it will be understood that such precise arrangement is not essential and that such cross-pin 22 need not extend entirely through the body and may be arranged differently with respect to the pin 16, all that is necessary being that a portion of a cross-pin shall enter a recess in the pin so as to serve as a stop to both inward and outward movement of the pin 16. Since the pin 16 is substantially of the full diameter of the bore in the last it can be made of a fairly large section and thereby obtain a satisfactorily large bearing on the interior of the bore in the block so that it becomes unnecessary to provide a metal ferrule or other lining for the bore 15 in the block. Further with the part 18 being made of reduced diameter, a recess is provided on all its sides between it and the walls of the bore 15^a so that the pin 16 may turn freely and can present all its sides for wear from time to time, thus preventing excessive wear on one side and preventing the pin from getting a "set" to one side by being always pressed in one direction. While the fastening pin is held and anchored in place by the cross-pin 22 in such manner that it is securely retained in place, it is possible if, for any reason, occasion should arise for the removal of the fastener to effect its ready removal by driving out or otherwise removing the cross-pin 22, whereupon the pin 16 can be readily removed, and with it the spring 21. These and other features of advantage combine to make my improved fastener a much more desirable construction than has heretofore been available.

It is to be understood that the drawing accompanying this specification is for the purpose of illustration only and that variations in and modifications from the present form shown may be resorted to, within the scope of my claims, without departing from my invention or sacrificing any of its advantages.

Having thus described my invention, I claim:

In a last comprising a body part and a separable block with registering bores, a pin in the bore in the body part and having two separated sections of substantially the same diameter as the bore and an intermediate

section and an end section both of reduced diameter, stop means in the body part and extending into said bore and in proximity to the intermediate section of reduced diameter, and a coil spring in the bottom of the bore in the body part and having the end section of reduced diameter received within its coils, substantially as set forth.

In testimony that I claim the foregoing, I hereto set my hand, this 19th day of December, 1914.

STEPHEN D. LAYMAN.
